(57) **CLAIM**

The ornamental design for a valve component storage device, as shown and described.

DESCRIPTION

FIG. 1 is a top perspective view of a valve component storage device showing my design, comprising a lower foam insert and an upper foam insert, in an in-use environment; FIG. 2 is a top perspective view of the lower foam insert of FIG. 1;

FIG. 3 is a top perspective view of the lower foam insert of FIG. 2;

FIG. 4 is a top elevational view of the lower foam insert of FIG. 2;

FIG. 5 is a bottom elevational view of the lower foam insert of FIG. 2;

FIG. 6 is a front view of the lower foam insert of FIG. 2;

FIG. 7 is a side view of the lower foam insert of FIG. 2;

FIG. 8 is a bottom perspective view of the upper foam insert of FIG. 1;

FIG. 9 is a bottom view of the upper foam insert of FIG. 8;

FIG. 10 is a top view of the upper foam insert of FIG. 8;

FIG. 11 is a front view of the upper foam insert of FIG. 8;

and, FIG. 12 is a side view of the upper foam insert of FIG. 8. The dashed broken lines shown in FIG. 1 illustrate an environmental container structure, which forms no part of the claimed design. The stippling in the figures shows a foam material.
